UNITED STATES PATENT OFFICE

144,981

DESIGN FOR A TOY MOUSE OR THE LIKE

Alfred Pelzmann, Chicago, Ill.

Application November 5, 1945, Serial No. 123,455

Term of patent 3½ years

(Cl. D34—2)

To all whom it may concern:

Be it known that I, Alfred Pelzmann, a citizen of the United States, residing at Chicago, in the county of Cook and State of Illinois, have invented a new, original, and ornamental Design for a Toy Mouse or the like, of which the following is a specification, reference being had to the accompanying drawing, forming part thereof.

In the drawing

Fig. 1 is a side elevational view of a toy mouse showing my new design;

Fig. 2 is a plan view of the same; and

Fig. 3 is a front elevational view of the same.

I claim:

The ornamental design for a toy mouse or the like, as shown.

ALFRED PELZMANN.
